(57) **CLAIM**

We claim the ornamental design for a pet feeding bowl, as shown and described.

DESCRIPTION

FIG. 1 is a perspective view of a pet feeding bowl showing a new design;

FIG. 2 is a front view thereof;

FIG. 3 is a rear view thereof;

FIG. 4 is a left-side elevation view thereof;

FIG. 5 is a right-side elevation view thereof;

FIG. 6 is a top plan view thereof;

FIG. 7 is a bottom plan view thereof;

FIG. 8 is a disassembled perspective view thereof; and, FIG. 9 is a perspective view showing a state of use for freely adjusting an angle thereof.

The broken lines shown in the drawings illustrate portions of the pet feeding bowl that form no part of the claimed design.
